UNITED STATES PATENT OFFICE.

EDWIN L. HARMON, OF GROTON, NEW YORK, ASSIGNOR TO CORONA TYPEWRITER COMPANY, INC., OF GROTON, NEW YORK, A CORPORATION OF NEW YORK.

TYPEWRITING-MACHINE.

1,387,979.

Specification of Letters Patent. Patented Aug. 16, 1921.

Application filed August 12, 1919. Serial No. 316,990.

To all whom it may concern:

Be it known that I, EDWIN L. HARMON, a citizen of the United States of America, and a resident of Groton, county of Tompkins, 5 and State of New York, have invented certain new and useful Improvements in Type-writing-Machines, of which the following is a full and clear specification.

This invention has relation to that type 10 of segment-shift covered by co-pending applications Petermann, Sr. 172,855, filed June 5, 1917, Armstrong, Sr. No. 256,675, filed Oct. 3, 1918, and Armstrong, Sr. No. 261,971, filed Nov. 11, 1918; and it has for its object the simplification and refinement of the 15 mechanism with the special end in view that its cost of manufacture as well as assembly in the machine shall be reduced to a minimum, as more fully hereinafter set forth.

20 In the drawings—

Figure 1 is a view partly in plan and partly in section showing the general arrangement of my improved devices in a type-writing machine frame;

25 Fig. 2 is a side elevation of the mechanism, the parts being shown in normal position and the machine-frame being broken away;

Fig. 3 is a similar view showing the segment carrier pulled down to its intermediate position;

Fig. 4 is a similar view showing the segment carrier pulled down to its lowermost position;

30 Figs. 5, 6 and 7 are fragmentary front views showing the parts respectively in the positions shown in Figs. 2, 3 and 4;

Figs. 8, 9, 10 and 11 are detail views of the locking devices for the two shift-key-levers;

40 Figs. 12 to 16 are views of details herein-after described.

In the drawings annexed, the numeral 15 designates a flat sheet-metal plate carrying 45 the usual segment 16, this plate being adapted to vertically slide on a pair of vertical posts 17 set in the frame near the back wall thereof. The segment supporting plate 15 has its two end portions bent forwardly and 50 then laterally outward, and the top and bottom edges of the outwardly extending plates of the angular end portions 18 are each provided with a rearwardly-extending ear 19 55 aforesaid posts 17 pass, thus slidably engag-

ing the segment-plate with said posts. Each post is fastened rigidly at its upper end to the forwardly-extending end-portion 20 of a vertical flat plate 21 affixed rigidly to the back wall of the frame, and each lower end of 60 the post is similarly affixed to a forwardly-extending ear 22 formed integral with said plate 21; and these lower ears 22 are each provided with an inwardly-extending ear 23. In this way, the slidable segment-carrying plate together with its guide-posts form a unitary structure which may be assembled 65 out of the machine and secured as a whole within the frame of the machine, thus simplifying manufacture and assembly of the 70 parts.

To raise and lower this segment, I employ a pair of arms 24, one arranged at each side of the machine and connected together at their forward ends by a rock-shaft 25 75 which extends transversely the full width of the machine-frame. This bar has its reduced pintle-like ends 26 journaled in blocks 27 fastened rigidly to the side-walls of the frame by screws 28; and the arms 24 are 80 fastened to this bar 25 by being provided with a hole which fits the cross-section (preferably rectangular) of said bar, each arm being provided with a pair of ears 29 which are struck up integrally from the sheet-metal arm and are fitted against opposite 85 faces of the bar, where they are suitably fastened as by brazing or welding. The rear end of each arm 24 is bifurcated to form two fingers 30 which extend through a 90 vertical slot 31 in the front plate of the adjacent angular end portion 18 of the segment carrier and thus form pivotal connection between the arms and the carrier, ears 32 being struck up from the front plates 95 of said portions 18 of the carrier to provide upper horizontal bearing-faces against which the rounded ends of the upper fingers 30 work in raising the segment. The lower fingers 30 work against ears 19 in pulling 100 the segment down. To normally hold the segment in its upper, normal position, I attach to each of the arms 24 a retractile spring 33, and the other, forward end of each spring is connected to a rigid transverse key-lever guide plate 34 by means of a screw 35, this screw affording means of varying the tension of the spring. In this way, the arms 24 are normally drawn upward, thus holding 105 the segment in its normal, upper position.

tion, in which position the top ears 19 abut solidly against set-screw-stops 36 carried by the upper stationary ears 20. When the segment is shifted to its lower or "figure" shift 5 position, set-screw-stops 37 on the end portions 18 of the carrier strike positively against the ears 23 on bars 21, and thus positively arrest the segment.

To swing down the arms 24 to thus pull 10 down the segment, I employ a pair of key-levers 38 and 39 at each side of the machine, each lever being fulcrumed on a transverse bar 40 affixed in the machine-frame and being provided with a rearwardly-extending 15 finger 41 forward of its fulcrum adapted when the key-lever is depressed to strike against the upper side of a lug 42 carried by the adjacent one of the arms 24 at the rear of the rock shaft 25. In this way, a 20 depression of any one of the levers 38 or 39 will cause the segment to descend, the duplication of the pairs of the levers being merely for the purpose of convenience of the operator. The shift-key levers are 25 yieldably held in normal position by springs 65 connecting said levers with plate 34, as shown in Fig. 2.

To wedge and lock the segment in its upper case position, as shown in Figs. 2 and 30 5, as well as to arrest it in its "Cap." shift or intermediate position, I employ the following devices: A flat bar 43 extending transversely of the machine is provided at its ends with upstanding arms 44 pivoted at 45 (near their lower ends) to upright ears 46 formed on the lower post-frame-ears 22, the pivots 45 permitting the upper ends of the arms to be swung forwardly and rearwardly. Each of the arms 44 is provided 35 with an inwardly-extending lug 47 which lies in a substantially horizontal plane in the path of fingers 48, which are virtually extensions beyond the fulcrum 40 of the key-levers, each of these fingers being bent upwardly at its rear extremity to lie just under the lug 47, so that when the key-lever is operated the finger connected therewith will bear against the under side of lug 47 and thus swing the upper ends of 40 the stop-arms 44 rearwardly. The forward edge of each of the lugs 47 is extended upwardly to form an ear 49 which forms a 45 convenient connection for a retractile spring 50 so arranged as to normally pull the stop-arms 44 forwardly.

In normal position, stop-arms 44 wedge 55 under adjustable stops 51 carried by forwardly-bent ears 52 formed on the front plates of end portions 18 of the segment carrier, the top ends of the arms being each provided with inwardly-extending ears 53 to form broad abutments for engagement with the stop-screws 51, the upper face of each ear 53 being inclined downwardly and 60 forwardly in its normal position so as to

wedge and lock the segment in its normal upper position. To arrest the segment in its middle or "Cap." shift position, I provide each of the top ears 19 with an adjustable screw-stop 54 similar in construction 70 to the screw-stops 51, which are adapted respectively to strike against the stop-lugs 53 on the upper ends of the arms 44 of bail 43, these arms 44 being swung backwardly far enough to bring the lugs 53 directly 75 under said stop-screws 54 by means of the finger 48 on either one of the levers 39, the parts being so proportioned as to swing the bail arms 44 to middle position (shown in Figs. 3 and 6) before the segment-carrying 80 plate is pulled down by means of the rock arms 24.

Fingers 48 attached to the shift-key-levers 38 are slightly longer than the corresponding fingers affixed to the other shift-levers 85 39, so that when the shift-levers 38 are actuated the bail arms 44 will be thrown farther back than when actuated by the levers 39. When thus thrown back to the limit of their rearward motion, the bail arms 44 will 90 be out of alinement with the stops 54 so that said stop-pins 54 will pass downwardly in front of the arresting lugs 53, and the segment-carrying plate will be arrested in its downward movement by the aforesaid stop-screws 37 hereinbefore described.

It is, of course, desirable that the shift-key-levers 38 and 39 shall be provided with means whereby they may be temporarily locked down, to thereby hold the segment 100 either in middle case position or lower case position. Any suitable devices may be used for this purpose. I prefer the device shown in Figs. 8 to 11, inclusive. In this locking mechanism, each of the shift-levers has pivoted to it at 56 an angle-lever 55, one of whose arms 57 extends upwardly and is provided with a supplemental key 58, and the other of whose arms 59 extends upwardly far enough to swing into contact with and 105 be arrested by the regular key 60 of the shift-lever whenever said supplemental key 58 is depressed by the operator. Coil-spring 61 serves to hold the supplemental key up and the stop-arm 59 away from its arrest- 110 ing key 60. When the shift-lever is depressed through the medium of the supplemental key 58, the angle-lever turns on its pivot 56 until the arm 59 comes against the main key 60; and then, as the shift-lever 115 descends, a lateral lock-lug 62 carried by the arm 57 impinges against the inclined face 63 of a stationary lug 64 (affixed to the frame of the machine) and snaps under the lower edge of said lug 64 and thus locks the 120 shift-lever down, the interlocking of the lug 62 with the under edge of lug 64 serving to prevent spring 61 from restoring the angle-lever to normal position. To release the shift-lever, it is simply necessary to 125 130

press down slightly on the main key 60, whereupon the lug 62 will be carried down far enough to be released from the stationary lock-lug 64, thereby permitting the 5 spring 61 to restore the supplemental key to normal position with respect to the main key.

The nature and scope of the invention 10 having been thus indicated and its preferred embodiment having been specifically described, what is claimed as new is:

1. A case-shift assembly unit comprising 15 a pair of upstanding brackets having horizontal ears adjacent the upper and lower ends thereof, a pair of vertical guide posts extending between the ears on the brackets and held to said ears, and a vertically slid- 20 able support having a pair of vertically spaced horizontal ears at each end thereof slidably held to the posts.

2. A case-shift assembly unit comprising 25 a pair of flat upstanding brackets provided with integral horizontal ears adjacent the upper and lower ends thereof, a sheet metal vertically disposed plate provided with a 30 pair of superposed integral horizontally disposed ears at each end thereof, a pair of vertical guide posts held at their upper and lower ends to the ears on the brackets and each extending loosely through the adjacent 35 pair of superposed ears on the plate, and a type-bar segment held to the plate.

3. A case-shift assembly unit comprising 40 a pair of upstanding brackets having super- 35 posed horizontal ears, a vertical guide post extending between the ears on each bracket and held thereto, a vertically slidable sup- 45 port extending between the brackets and provided at each end with a pair of super- 50 posed horizontal ears through which the ad- 55 jacent guide post extends, the ears on the support being located between the ears on the brackets and coöperating therewith to limit the up and down movement of the sup- 60 port, and a downwardly facing stop carried by one of the upper ears of the support.

4. A case-shift assembly unit comprising 65 a pair of upstanding brackets having super- 55 posed horizontal ears, a vertical guide post extending between the ears on each bracket and held thereto, a vertically slidable sup- 60 port extending between the brackets and provided at each end with a pair of super- 65 posed horizontal ears through which the ad- 70 jacent guide post extends, the ears on the support being located between the ears on the brackets and coöperating therewith to limit the up and down movement of the sup- 75 port, a pair of downwardly facing stepped stops carried by one of the upper ears of the support, and a type-bar segment held to the support.

5. A case-shaft assembly unit comprising 80 a pair of upstanding brackets having for- 85 wardly extending ears adjacent their upper

and lower ends, a flat sheet metal vertically disposed plate having its side edges bent forwardly and then laterally outward, a type-bar segment held to the front face of the plate, a pair of vertically spaced horizontal 70 ears extending rearwardly from each outwardly bent end portion of the plate, said outwardly bent end portions of the plate being provided with vertical slots extending between said ears, a third rearwardly ex- 75 tending ear on the outwardly bent end portions of the plate above the other ears, the upper and lower ears being provided with apertures out of alinement with the intermediate ears, and a pair of vertical guide 80 posts held to the ears on the brackets and extending through the apertures in the upper and lower ears on the end portions of the plate.

6. A case-shift assembly unit comprising 85 a pair of upstanding brackets having for- 90 wardly extending ears adjacent their upper and lower ends, a flat sheet metal vertically disposed plate having its side edges bent forwardly and then laterally outward, a type-bar segment held to the front face of the plate, a pair of vertically spaced horizontal ears extending rearwardly from each outwardly bent end portion of the plate, said outwardly bent end portions of the plate being provided with vertical slots extending 95 between said ears, a third rearwardly ex- 100 tending ear on the outwardly bent end portions of the plate above the other ears, the upper and lower ears being provided with apertures out of alinement with the intermediate ears, and a pair of vertical guide posts held to the ears on the brackets and extending through the apertures in the upper and lower ears on the end portions of the plate, a downwardly extending stop held to each upper ear on the outwardly bent end portions of the plate, and a down- 105 wardly and rearwardly extending stop held to each outwardly bent portion of the plate 110 below the stops on the upper ears.

7. In a typewriting machine, a main frame, a pair of vertical segment-guides and supporting members adapted for attachment to the back-wall of said main frame, a segment-carrying plate slidingly mounted on said guides and arresting stops carried thereby, the segment-arresting device supported on said members, the foregoing parts being attachable to the frame 115 as a unit, and a shift-key mechanism for operating the segment-carrying plate as well as said arresting device.

8. In a typewriting machine, a segment- 120 carrying plate provided with rearwardly extending lugs, and shift-key-operated devices for actuating said segment-plate em- 125 bodying a pair of arms whose rear ends extend rearwardly beyond the face of the segment-plate and engage said lugs. 130

9. In a typewriting machine, a sheet-metal segment-carrying-plate and means for vertically guiding it in case-shifting, said plate being vertically slotted and provided with rearwardly-extending lugs, and shift-key-operated devices for pulling the plate down embodying a pair of arms whose rear ends extend into said slots and engage said lugs.
10. In a typewriting machine, the combination of a main frame, a type-bar segment support and guiding means therefor removable as a unit from the frame, support-locking and position-determining means removable from the frame with the support and its guiding means, and key-operated means mounted in the frame for shifting the support and controlling said position-determining and support-locking means and separably connected therewith.
11. In a typewriting machine, the combination of a main frame, a type-bar segment support, guiding and arresting means for the support mounted in the frame and removable with the support as a unit from the frame, a rock shaft extending transversely of the frame, bearing for said shaft separably held to the frame, a pair of rock arms rigidly held to the shaft and separably connected with the support, and a pair of shift key levers pivotally supported in the frame and separably connected with one of the rock arms.
12. In a typewriting machine, the combination of a main frame; a type-bar segment support and guiding means therefor removable as a unit from the frame, stops removable with the support and its guiding means for arresting the support in its uppermost and lowermost positions, a swinging member removable with the support and its guiding means, stepped stops on the support adapted to be engaged by said swinging member to respectively lock the support in its uppermost position and arrest the support in an intermediate position, a rock shaft extending transversely of the frame and removably supported therein, rock arms extending fore and aft of the frame held to said shaft and having separably interlocked rocking connections with the support, spring means for normally swinging the rock arms upwardly, and a pair of shift-key levers loosely engaging one of said arms for rocking the arms downwardly and loosely engaging said swinging member and adapted to swing said member different distances from locking position.
13. In a typewriting machine, the combination of a support shiftable different distances in the same direction from a normal position to vary the relation between printing instrumentalities and a platen, key-operated means for shifting the support, means for arresting the support at its normal and maximum case shift positions, a pair of stepped abutments on the support, and a swinging member mounted independently of the support and normally engaging one of said abutments to lock the support in its normal case shift position, said member being shiftable different distances by the key-operated means to move the same either into or out of the path of the other abutment on the support.
14. Double case shift mechanism for typewriting machines comprising a support movable vertically to change case, means for arresting the support in its uppermost and lowermost positions, a pair of stepped abutments on the support, a swinging member mounted independently of the support provided with an abutment normally engaging one of the abutments on the support to lock the support at one limit of its movement, a pair of shift-keys connected with the support for shifting the same toward the other limit of its movement, and connections between said keys and said member for positioning the member in the path of the other abutment on the support when one key is operated and for shifting the member to an inactive position when the other key is operated.
15. Double case shift mechanism for typewriting machines comprising a support shiftable vertically to change case, means for normally moving the support upward, means for determining the uppermost and lowermost positions of the support, a pair of stepped abutments on the support, an upstanding swinging arm provided with an abutment normally engaging one of said abutments on the support to lock the support in its uppermost position, and a pair of shift keys operatively connected to shift the support downward and adapted to shift the swinging arm different distances from support-locking position, the abutment on said arm being shifted into the path of the other abutment on the support when one of the keys is operated to arrest the support in an intermediate position.
16. Double case shift mechanism for typewriting machines comprising a support shiftable vertically to change case, two stepped stops mounted at each end of the support, a bail having upstanding side arms pivotally supported to swing fore and aft of the machine and each provided with a laterally extending projection, a spring for rocking the bail in one direction to cause the lugs on the bail arms to engage under the lowermost stops on the support, means for normally moving the support upward, a pair of shift keys connected with the support for shifting the support downward, and connections between the keys and bail for moving the lugs on the bail arms into the path of the uppermost stops on the support.

when one key is operated and to move said lugs to inactive position when the other key is operated.

17. In a typewriting machine, the combination of a main frame, a support shiftable vertically to change case, means for guiding the support, a transverse rock shaft journaled in the frame forward of the support, a pair of rock arms held to said shaft at 10 their forward ends and connected at their rear ends with the support, a key-lever guide plate held in the frame forward of the shaft, a pair of coil springs connected with the rock arms and said plate for 15 rocking the arms upward, and a shift-key lever fulcrumed at a point in the frame at the rear of the rock shaft and connected with one of the rock arms at a point intermediate its fulcrum and the rock shaft for 20 shifting the support downward.

18. In a typewriting machine, the combination of a main frame, a support shiftable vertically to change case, means for guiding the support, a transverse rock shaft jour- 25 naled in the frame forward of the support,

a pair of rock arms held to said shaft at their forward ends and connected at their rear ends with the support, a key-lever guide plate held in the frame forward of the shaft, a pair of coil springs connected with the 30 rock arms and said plate for rocking the arms upward, one of said rock arms having a laterally extending projection at the rear of the rock shaft, a shiftable member for locking the support in its uppermost position and movable to two different positions from its locking position in one of which it is adapted to arrest the support in an intermediate position and in the other of which it permits movement of the support 35 to its lowermost position, a pair of shift key levers fulcrumed at the rear of the projection on the rock arm and overlying said projection, and connections between said levers and members for shifting the member 40 different distances.

This specification signed this 5th day of August A. D. 1919.

EDWIN L. HARMON.
